ATTORNEYS.

UNITED STATES PATENT OFFICE.

EDWARD JOHN RYAN, OF DANVILLE, ILLINOIS.

HEAT AND PRESSURE REGULATOR.

No. 894,062.

Specification of Letters Patent.

Patented July 21, 1908.

Application filed January 9, 1908. Serial No. 409,921.

To all whom it may concern:

Be it known that I, EDWARD JOHN RYAN, a citizen of the United States, and a resident of Danville, in the county of Vermilion and State of Illinois, have made certain new and useful Improvements in Heat and Pressure Regulators, of which the following is a specification.

My invention is an improvement in heat and pressure regulators and consists in certain novel constructions and combinations of parts hereinafter described and claimed.

Referring to the drawings forming a part hereof—Figure 1 is a longitudinal section 15 through the device, Fig. 2 is a section of the upper end of the device taken at a right angle to Fig. 1, Fig. 3 is a bottom plan view of one of the valves, and Fig. 4 is an enlarged section of one of the valves.

20 The present embodiment of my invention, comprises a casing 1, connected at one end by a pipe 2 with the boiler 2^a, and at the other end by a pipe 3 with the expansion tank 4. A fitting 5 is arranged between the 25 end of the casing and the pipe 3 and a valve casing 6 is arranged between the casing and the pipe 2. A pipe 7 connects the fitting 5 with a valve casing 8, which in turn is connected to the valve casing 6 by a pipe 9.

30 A valve seat 10 is provided in the casing 6, and a valve 11 normally rests on and closes the opening through the seat. The said valve is provided outside of the seat with a plurality of spirally arranged blades or vanes 35 12, and on its upper face with a threaded lug 13, which engages a threaded opening 14 in the lower end of a weight 15 movable vertically in the casing 1. The upper end of the weight is provided with an opening 16 in 40 which is received a pin 17, on a cross bar 18 arranged within the fitting, the pin being designed to guide the weight in its vertical movement. The weight 15 may be of any desired heaviness, and is designed to keep the 45 valve 11 closed until the water in the boiler attains a predetermined pressure. When this pressure is attained, the weight will be lifted, thus permitting the water to escape into the casing 1 and from thence into the 50 expansion tank 4. A valve is also provided for permitting water to pass from the expansion tank to the boiler, when the pressure in the boiler falls below a predetermined pressure. For this purpose the casing 8 is 55 provided with a valve seat 19, upon which normally rests a valve 20, the valve being

provided with the spiral blades or vanes 12, before mentioned, and with a threaded lug 21 on its upper surface. The threaded lug engages in a threaded opening 22 of a weight 60 23, mounted for vertical movement in the pipe 9, and guided at its upper end by a pin 24 received in an opening in the end of the weight, and secured to a cross bar 25 in the casing 6. The weight 23 may be made of 65 any desired heaviness, so that when the pressure in the boiler falls below a predetermined level, water will be admitted from the expansion tank to the boiler.

By means of the improvement, the pressure of the water in the boiler may be maintained constantly at a predetermined amount, the pressure being restored automatically when it passes above this predetermined point, or below it. The arrangement of the 75 spiral blades on the valves, provides for a turning movement of the said valves whereby to provide a constant renewal of the valve surface and to prevent the lodgment of foreign substances between the valve and its 80 seat.

I claim—

1. The combination with the boiler and expansion tank, of a casing provided with a valve seat, pipes connecting the casing with 85 the boiler and the tank, a valve coöperating with the seat to close the communication from the boiler to the tank, a weight having an opening in its upper end detachably connected with the valve, a cross bar in the casing provided with a pin for engaging the opening of the weight whereby to guide the same, a pipe leading from the tank to the boiler, a valve controlling the communication through the pipe, a weight detachably connected with the valve, and means for guiding the movement of the valve, each of said valves being provided with spirally arranged vanes for the purpose set forth.

2. The combination with the boiler and 100 expansion tank, of a casing provided with a valve seat, pipes connecting the casing with the boiler and the tank, a valve coöperating with the seat to close the communication from the boiler to the tank, a weight having 105 an opening in its upper end detachably connected with the valve, a cross bar in the casing provided with a pin for engaging the opening of the weight whereby to guide the same, a pipe leading from the tank to the 110 boiler a valve controlling the communication through the pipe, a weight detachably con-

nected with the valve, and means for guiding the movement of the valve.

3. The combination with the boiler and the expansion tank, of a casing provided with 5 a valve seat, pipes connecting the casing with said boiler and tank, a valve coöperating with the seat to close the communication between the boiler and the tank, a weight detachably connected with the valve, means 10 for guiding the movement of the weight, a pipe leading from the tank to the boiler, a valve in the pipe for preventing movement of fluid from the tank to the boiler, a weight detachably connected with the valve and 15 means for guiding the weight.

4. The combination with the boiler and expansion tank, of a plurality of pipes connecting the boiler and the tank, a valve in 20 one of said pipes for preventing movement of fluid from the tank to the boiler, a weight in connection with said valve for retaining said valve closed against movement of fluid from the boiler to the tank below a predetermined pressure in the boiler, a valve in the

other pipe preventing movement of fluid 25 from the boiler to the tank, and means in connection with said valve for permitting the passage of fluid from the tank to the boiler when the pressure in the boiler falls below a predetermined value. 30

5. The combination with the boiler and the expansion tank, of a plurality of pipes connecting the tank and the boiler, means in 35 one of said pipes for preventing passage of fluid from the tank to the boiler and for permitting passage of fluid from the boiler to the tank when the pressure in the boiler exceeds a predetermined value, and means in the other pipe for preventing the passage of fluid from the boiler to the tank, but permitting 40 passage of the fluid from the tank to the boiler when the pressure in the boiler falls below a predetermined value.
